US00D717285S

(12) **United States Design Patent**
Fahlgren et al.

(10) **Patent No.:** **US D717,285 S**
(45) **Date of Patent:** **** Nov. 11, 2014**

(54) **HANDSET**

(75) Inventors: **Anton Fahlgren**, Helsinki (FI); **Casper Asmussen**, Malmö (SE)

(73) Assignee: **Nokia Corporation**, Espoo (FI)

(**) Term: **14 Years**

(21) Appl. No.: **29/432,377**

(22) Filed: **Sep. 14, 2012**

Related U.S. Application Data

(63) Continuation of application No. 29/410,967, filed on Jan. 13, 2012, now Pat. No. Des. 672,329, which is a continuation of application No. 29/386,702, filed on Mar. 3, 2011, now Pat. No. Des. 652,403.

CLAIM

The ornamental design for a handset, as shown and described.

DESCRIPTION

FIG. 1 is a perspective view of a handset showing our new design;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a rear view thereof.

The broken lines showing the remainder of the handset are directed to environment and are for illustrative purpose only; the broken lines form no part of the claimed design.

1 Claim, 5 Drawing Sheets
